DESIGN FOR AN AUXILIARY LAMP FOR VEHICLES

Graham Trippe, Chicago, Ill.

Application October 27, 1938, Serial No. 80,715

Term of patent 14 years

To all whom it may concern:

Be it known that I, Graham Trippe, a citizen of the United States of America, residing at Chicago, Illinois, have invented a new, original, and ornamental Design for an Auxiliary Lamp for Vehicles, of which the following is a specification, reference being had to the accompanying drawing, forming a part thereof.

Fig. 1 is a front elevational view of an auxil-

iary lamp for vehicles, showing my new design; and Fig. 2 is a perspective view thereof;

Fig. 3 is a rear elevational view of the same drawn on a reduced scale.

I claim:

The ornamental design for an auxiliary lamp for vehicles, substantially as shown.

GRAHAM TRIPPE.
